(57) **CLAIM**

The ornamental design for an in-line ground fault circuit interrupter (GFCI), as shown and described.

DESCRIPTION

FIG. 1 is a top perspective view of the in-line ground fault circuit interrupter (GFCI) employing our new design;

FIG. 2 is a top view of FIG. 1;

FIG. 3 is a bottom view of FIG. 1;

FIG. 4 is a right side view of FIG. 1;

FIG. 5 is a left side view of FIG. 1;

FIG. 6 is a front end view of FIG. 1; and,

FIG. 7 is a rear end view of FIG. 1.

The broken lines in the drawings represent portions of the in-line ground fault circuit interrupter (GFCI) that form no part of the claimed design.
